Primary Examiner — Daniel J Domino*Assistant Examiner* — Lee D. Starr**CLAIM**

The ornamental design for a medicament delivery device cover, as shown and described.

DESCRIPTION

FIG. 1 is a front view of a medicament delivery device cover;

FIG. 2. is a front perspective view of the medicament delivery device cover;

FIG. 3 is a rear perspective view of the medicament delivery device cover; and,

FIG. 4 is a top left perspective view of the medicament delivery device cover.

In the drawings, the dashed lines (--) depict portions of the article that form no part of the claimed design. The additional dash line structure at the top of FIG. 2 depicts portions of the article that form no part of the claimed design.
